[57] CLAIM

The ornamental design for a corner indicator for caller ID display device, as shown and described herein.

DESCRIPTION

FIG. 1 is a front-right side perspective view of the corner indicator showing our design.

FIG. 2 is a right side orthogonal view of the corner indicator of FIG. 1.

FIG. 3 is a top orthogonal view of the corner indicator of FIG. 1.

FIG. 4 is a rear orthogonal view of the corner indicator of FIG. 1; and,

FIG. 5 is a bottom orthogonal view of the corner indicator of FIG. 1.

The broken line showings of a caller ID display device throughout the views are for illustrative purposes only and form no part of the claimed design.
